UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILLING APPARATUS.

1,214,603.

Specification of Letters Patent.

Patented Feb. 6, 1917.

Application filed February 23, 1916. Serial No. 80,015.

To all whom it may concern:

Be it known that I, WILLIAM A. SMITH, a citizen of the United States, residing at Denver, in the county of Denver and State of Colorado, have invented certain new and useful Improvements in Rock-Drilling Apparatus, of which the following is a specification.

The present invention relates to rock drilling apparatus, and more particularly of the type set forth in my copending application, Serial No. 68,794, filed December 27, 1915.

One of the objects of the present invention is to provide a structure that is more compact and highly effective.

A further object is to provide means whereby the mechanism can be utilized as a device for manually turning the drilling apparatus.

Another object is to provide mechanism whereby the exhaust from the turning motor is utilized to keep the bearings clear of dirt and dust, thereby preventing excessive wearing.

Another and important object is to provide a holding handle which also constitutes means for controlling the supply of motive fluid to the turning motor, said handle being so constructed and arranged that if released, the fluid supply is automatically cut off, thereby avoiding danger of damage and injury to the operator.

In the embodiment disclosed, Figure 1 is a side elevation of the apparatus in assembled condition, the parts being broken away. Fig. 2 is a vertical longitudinal sectional view on an enlarged scale through the motor. Fig. 3 is a horizontal sectional view. Fig. 4 is a sectional view on the line 4-4 of Fig. 3. Fig. 5 is a cross sectional view through the motor. Fig. 6 is a detail perspective view of the piston. Fig. 7 is a similar view of the distributing valve. Fig. 8 is a detail sectional view on an enlarged scale of the throttle valve and associated parts. Fig. 9 is a cross sectional view on the line 9-9 of Fig. 8. Fig. 10 is a detail sectional view through a portion of the throttle valve and its seat, showing the lubricant discharge port. Fig. 11 is a detail sectional view illustrating the locking means for the gearing. Fig. 12 is a view at right angles to Fig. 11.

Similar reference numerals designate cor-

responding parts in all the figures of the drawings.

In the embodiment disclosed, drilling apparatus of a well known type is illustrated, the same comprising a fluid-operated motor 13, provided at one end with a chuck for receiving a drill bit 14 and having at its other end fluid-operated feeding means 15. Fluid is supplied to the motor and feeding means through a hose line 16 controlled by a throttle valve 17 in a manner well understood.

As in the above-mentioned case, the invention is shown in the form of an attachment, comprising a turning motor, this motor including a cylinder member 18 having an offset gear casing 19 composed of two parts held together by bolts 20.

Located in the gear casing 19 is a gear wheel 21 carried by a sleeve 22 that projects above the casing, having a rib 23 overlapping the upper edge thereof, said sleeve terminating in an outstanding flange 24 that is provided with holes through which the side bolts 25 of the drilling motor 13 pass. It will thus be seen that the sleeve 22 and consequently the gear 21 are rigidly affixed to the motor and all rotate in the gear case 19.

In the cylinder member 18 is a reciprocating piston 26 provided between its ends with an integral rack 27 that meshes with the gear wheel 21, the cylinder member 18 and gear case 19 being in communication with each other, as will be clear by reference to Fig. 3 to permit such a meshing action. This piston is supplied with motive fluid through a tube 28 fixed to one end of the cylinder member and slidably received in a central longitudinal chamber 29 formed in the piston. Located alongside the chamber 29, adjacent one end thereof, is a valve chamber 30 having communication with the chamber 29, through a port 31. Leading from the valve chamber 30 on opposite sides of the port 31 are supply and exhaust passages 32 and 33 that extend longitudinally in the piston, and respectively open through the opposite ends thereof. Exhaust ports 34 and 35 communicate with the end portions of the valve chamber 30, and also communicate with external chambers 36 and 37 formed by cutting away the body of the piston 26 between its ends, these chambers being disposed on opposite sides of the rack 110

27 and having communication with the interior of the gear casing 19, as will be clearly evident by reference to Fig. 5.

Operating in the valve chamber 30 is a 5 distributing valve 38 having a central enlargement 39, end enlargements 40 and stems 41 and 42 that respectively project beyond the ends of the piston 26, said stems being arranged to respectively strike the heads of 10 the cylinder upon the reciprocation of the piston.

The two cylinder heads are respectively designated 43 and 44 and are held upon the body of the cylinder by side bolts 45. One 15 of these cylinder heads 44 is enlarged and provided with a lubricant-holding reservoir 46, through the center of which is formed a conduit 47 communicating with the tube 28. A lateral port 48 opens through one 20 side of the cylinder head 44 and communicates with the conduit 47, said port receiving a suitable coupling by which a motive fluid supply line 49 can be connected thereto. The conduit 47 is provided with a taper 25 valve seat 50, and as shown more particularly in Fig. 10, a discharge port 51 from the lubricant reservoir 46 opens into this valve seat.

The cylinder head 44 also carries a handle. 30 This handle comprises a stem 52, one end of which is threaded into the outer end of the head 44, the other end being externally threaded, as illustrated in Fig. 2. The stem has a longitudinal opening therethrough in 35 which is slidably mounted a plug valve 53 that is movable into and out of coaction with the seat 50, to not only control the passage of motive fluid through the tube 28, and thence into the piston, but also the supply of lubricant through the port 51. The outer end of the valve stem 53 is secured to 40 a washer 54 detachably but non-rotatably engaged in the outer end of a handle grip 55 mounted upon the outer end of the stem 52. The said stem 52 terminates short of the washer 54 forming an internal chamber, in 45 which is located a coiled spring 56. One end of this spring, as shown at 57, is engaged in the end of the stem 52, the other end 58 of 50 said spring passing through the washer 54 and being engaged in an opening 59 in the end of the handle grip.

By referring to Figs. 2 and 3, it will be seen that the tube 28 is held in place by 55 having a flange 60 at its outer end, which is clamped between a head disk 61 and the cylinder head 44, a packing washer 62 being arranged against the flange to prevent leakage. It will also be seen by reference to 60 Fig. 9 that lubricant can be supplied to the reservoir 46 through an opening 63 normally closed by a removable plug 64 threaded thereinto.

It is believed that the operation of the 65 device can now be made clear. When in po-

sition on drilling apparatus, as shown in Fig. 1 and as already explained, the gear 21 is fixed against movement with respect to said drilling apparatus. If motive fluid is supplied through the line 49, it will enter 70

the conduit 47, but as the normal position of the valve 53 is a closed one, this motive fluid cannot pass into the tube 28. In the operation of the device, the handle 55 is grasped by the operator to hold the motor against 75

turning, and it will be noted that this handle also constitutes means for controlling the supply of motive fluid to the motor. To admit such fluid, the operator turns the grip 55 and thus moves the same on the stem 52. 80

As a consequence the valve 53 will move with it and be unseated to any extent desired. When the valve is thus opened, the motive fluid will pass through the tube 28 into the chamber 29, and thence into the 85

valve chamber 30. Assuming the parts, as shown in Fig. 2, it will be seen that the motive fluid will pass through the port 32 and enter the cylinder behind the piston, thereby moving said piston to the left. The exhaust 90

will take place through the channel 33, port 35 and chamber 37. As the piston approaches the end of its left hand stroke, the stem 42 will strike the cylinder head and the valve will be shifted, whereupon the 95

motive fluid from the valve chamber 30 will pass through the channel 33, while the exhaust will now take place through the channel 32, port 34 and chamber 36. The piston will thus be reversed in its movement and be returned to the position illustrated in 100

Fig. 2. The reciprocation of the piston through the medium of the rack 27 and gear 21 will cause the oscillation of the drilling apparatus, and in this connection, it will be 105

noted that the exhaust will pass into the gear case 19 around the gear and escape through the joints of said gear case, these joints being sufficiently open to permit its ready escape. As a consequence, the dirt 110

and dust will be blown away from the gear case, and the interior with the gearing and bearings kept free therefrom. When the valve 53 is opened, it will be evident by reference to Fig. 10 that the lubricant port 51 115

will also be opened, and consequently a small amount of lubricant will be continually passing with the motive fluid into the machine and find its way to all the parts. Inasmuch as the opening of the valve places 120

tension on the spring 56, it will be evident that if the handle is released by accident or otherwise, the handle grip will be automatically turned by the spring to again close the valve. Consequently if an accident should 125

happen and the operator lose hold upon the handle grip, the motor will automatically stop and danger from an uncontrolled operating device will thereby be eliminated.

It may sometimes be desirable to turn the 130

drilling apparatus by hand, and in order that this may be done, means are provided for locking the turning motor to the gear 21, so that said motor with the handle will 5 be rigidly fixed with respect to the drilling apparatus. In the present embodiment, this locking means is shown in the form of a rotary cam element 65 journaled in the gear case 19 at its juncture with the cylinder 27, 10 and having a central cut-away portion 66, which when turned to the proper position, will permit the passage of the gear teeth, as shown in Fig. 11. If, however, the device is given a half turn, the cam will pass 15 between two of the teeth and thus prevent the relative rotation of the gear wheel 21 and the motor. This locking device, not only has a rotary movement, but it is also capable of longitudinal movement. It is 20 provided at one end with a finger grip 67 and at its other end with a cross pin 68 that is arranged to engage in notches 69 formed in the lower portion of the casing in which the device is rotatably mounted. 25 A coiled spring 70, interposed between the finger piece 67 and the casing, serves to hold the cross pin 68 in the notches, and thus lock the device, both in its operative and in its inoperative positions.

30 From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

35 Having thus fully described my invention, what I claim as new, and desire to secure by Letters Patent, is:—

1. The combination with drilling apparatus, of a motor movably mounted on the 40 drilling apparatus for turning the same, means for supplying actuating fluid to the motor, and a common handle for holding the motor against turning with the drilling apparatus and controlling the supply of 45 actuating fluid to the motor.

2. The combination with drilling apparatus, of a motor movably mounted on the 50 drilling apparatus for turning the same, means for supplying actuating fluid to the motor, a device controlling the actuating fluid supply to the motor, and a handle for holding the motor against turning with the drilling apparatus, said handle being movable on the motor and controlling the supply 55 of actuating fluid thereto.

3. The combination with drilling apparatus, of a motor movably mounted on the 60 drilling apparatus for turning the same, means for supplying actuating fluid to the 65 motor, a valve controlling the fluid supply

to the motor, and a handle connected to the motor for holding the latter against turning, said handle being rotatably mounted on the motor and having a connection with the valve for operating it. 70

4. The combination with drilling apparatus, of a motor movably mounted on the drilling apparatus for turning the same, means for supplying actuating fluid to the motor, a common handle for holding the 75 motor against turning with the drilling apparatus and controlling the supply of actuating fluid to the motor, and means for normally maintaining the handle in a position to cut off the supply of fluid to the 80 motor.

5. The combination with drilling apparatus, of a motor movably mounted on the drilling apparatus for turning the same, means for supplying actuating fluid to the 85 motor, a device controlling the actuating fluid supply to the motor, a handle for holding the motor against turning with the drilling apparatus, said handle being movable on the motor and controlling the supply of 90 actuating fluid thereto, and means for yieldingly maintaining the handle in a position to cut off the supply of fluid to the motor and cause it to assume such position when in released condition. 95

6. The combination with drilling apparatus, of a motor movably mounted on the drilling apparatus for turning the same, means for supplying actuating fluid to the motor, a valve controlling the fluid supply 100 to the motor, a handle connected to the motor for holding the latter against turning, said handle being rotatably mounted on the motor and having a connection with the valve for operating it, and a spring connected to the handle for normally and yieldingly holding it in a position to maintain 105 the valve closed.

7. The combination with drilling apparatus, of a reciprocating motor disposed 110 transversely thereof and including a cylinder member, gearing between the motor and drilling apparatus for turning the latter from the former, a handle projecting from one end of the cylinder member, means at 115 said end for supplying motive fluid to the motor, said handle being rotatably mounted on the cylinder member, a valve connected to the handle and controlled thereby, and a spring engaged with the handle for normally holding it with the valve in closed 120 position.

8. The combination with drilling apparatus, of a handle therefor, said apparatus and handle being relatively rotatable, means 125 other than the handle for turning the apparatus when said handle and apparatus are relatively rotatable, and means for locking the handle and drilling apparatus against relative rotation. 130

9. The combination with drilling apparatus, of a handle therefor, said apparatus and handle being relatively rotatable, means movably mounted on the handle for turning the drilling apparatus, and means for locking the handle and drilling apparatus against relative rotation to permit the latter being manually turned. 60
10. The combination with drilling apparatus having a gear element, of a motor including a gear element coacting with said first gear element, means for locking the gear elements to hold the motor and drilling apparatus against relative movement, and means for turning the apparatus when the gears are so locked. 65
11. The combination with drilling apparatus, of a gear element thereon, a motor having a rotatable mounting on the drilling apparatus and including a gear element coacting with the first-mentioned gear element, and means engaging one of the gear elements for holding the drilling apparatus and motor against relative movement, said motor being 70 rotatable with the apparatus when so held against relative movement. 75
12. The combination with rotatable drilling apparatus, of a gear thereon, a motor disposed transversely of the drilling apparatus and including a gear element coacting with the first mentioned gear, a rotatable locking device mounted on the motor and having a portion arranged to engage the teeth of the gear on the drilling apparatus to lock the motor and drilling apparatus against relative rotation, and a handle on the motor for holding the same and for manually turning the drilling apparatus when locked. 80
13. The combination with drilling apparatus, of a gear fixed thereto, a cylinder member disposed transversely of the drilling apparatus, and a reciprocatory piston operating in the cylinder member and having a rack between its ends meshing with the gear for turning the drilling apparatus. 85
14. The combination with drilling apparatus, of a gear fixed thereto, a cylinder member disposed transversely of the drilling apparatus, a reciprocatory piston operating in the cylinder member and having a rack between its ends meshing with the gear, and a handle grip projecting from the cylinder member for holding the same against turning with the drilling apparatus. 90
15. The combination with drilling apparatus, of a turning motor therefor, gearing between the motor and drilling apparatus for effecting the turning movement of the latter, and means for directing the exhaust from the motor against the gearing. 95
16. The combination with drilling apparatus, of a turning motor therefor, gearing between the motor and drilling apparatus for effecting the turning movement of the latter, a casing for the gearing, and means for directing the exhaust from the motor into and through the gear casing. 100
17. The combination with drilling apparatus, of a gear surrounding the same, a motor cylinder including a gear casing surrounding the gear and motor, said drilling apparatus being rotatable in the gear casing, a reciprocatory piston in the cylinder member having a rack meshing with the gear, means for supplying motive fluid to the cylinder member, and means for directing the exhaust from the cylinder member through the gear casing. 105
18. As an attachment, a tubular gear having means for attachment to drilling apparatus, a cylinder member having a gear casing in which the gear is rotatably mounted, a piston operating in the cylinder member and having a rack between its ends meshing with the gear, means for supplying motive fluid to the cylinder member, and a handle on one end of the cylinder member for holding it, said handle constituting means for controlling the fluid supply. 110
19. The combination with drilling apparatus, of a motor for turning the same, a handle for manually turning the drilling apparatus, said drilling apparatus being rotatable with respect to the handle when the turning motor is in operation, and means for locking the handle and drilling apparatus against relative rotation to permit the manual rotation of the latter by the handle. 115
20. The combination with drilling apparatus, of a handle for manually turning the same, said handle having rotatable engagement with the apparatus, a motor for automatically turning the drilling apparatus, said motor having a gear connection with the drilling apparatus, and means for securing the drilling apparatus and handle against relative rotation to permit the drilling apparatus to be manually rotated through the medium of the handle. 120

In testimony whereof I affix my signature in the presence of two witnesses.
